CENTRALIZED TRAFFIC CONTROLLING SYSTEM FOR RAILROADS

Darrol F. De Long, Rochester, N. Y., assignor to
General Railway Signal Company, Rochester,
N. Y.

Application September 11, 1935, Serial No. 40,114

9 Claims. (Cl. 177—353)

This invention relates to centralized traffic controlling systems for railroads, and it more particularly pertains to the communication part of such systems.

5 By means of the centralized traffic controlling system contemplated by the present invention, a central control office is placed in communication with a number of outlying field stations in such a way that controls may be transmitted to these 10 field stations for governing the operation of traffic controlling devices located at the various stations. Likewise, the conditions of the various traffic controlling devices at each station are transmitted from each station to the control office 15 to advise the operator of the location of trains and the condition of the traffic controlling devices, such conditions being transmitted as indications.

The present invention more particularly relates 20 to a centralized traffic controlling system wherein the supervision of the traffic governing devices and the indication of their conditions are accomplished over a communication system comprising two line circuits, namely, a control line circuit 25 and an indication line circuit. The present invention is more particularly directed to a traffic controlling system in which a repeater station is provided when the distance between certain of the field stations and the control office is such 30 that it is impractical to transmit impulses between the control office and these certain field stations without the use of undesirably high line voltages and/or unduly large line conductors, because 35 of the length of the line circuits.

35 An important feature of the present invention is a storage and repeater arrangement, whereby it is possible to store indications from a distant station in the repeater station during one half-step of the stepping mechanisms and repeat the 40 stored indications from the repeater station to the office during the next half-step of the stepping mechanisms.

In accordance with another feature of the 45 present invention it is possible to operate one or more laterals or branches extending from the main line of the communication system without the necessity of looping the line circuits of such laterals in series with the main line circuit, with the consequent need of high voltage and/or large 50 line conductors. It will be obvious from the description which follows that the repeater station as disclosed in the present invention may be installed at the locations where such laterals branch off from the main line, irrespective of 55 whether this branch is made at the end of the

main line or at some location between the office and the end of the line. It will also be obvious that laterals may be branched off the above mentioned laterals by means of the repeater arrangement disclosed, all within the scope of the 5 present invention.

Another object of the present invention is the provision of a repeating circuit so arranged that the system will operate at its desired speed without the need of increasing the size of the line 10 conductors or providing line voltages beyond a reasonable value. As a result of the repeating arrangement provided in the present invention, installation costs of a centralized traffic controlling system are reduced because it is possible to keep 15 the size of the line battery and the line conductors down to a minimum. In other words the present circuit arrangement is so arranged that when the economical limit of line wire size is reached and the economical limit of battery size 20 is reached, the line circuit will be arranged to repeat into another line circuit for the transmission of controls and indications, with this process repeated as often as required.

Another object of the present invention is the 25 provision of a circuit arrangement for directly repeating impulses from a primary control line circuit in straight time cascade into a secondary control line circuit.

Another object of the present invention is the 30 provision of a storage arrangement in the repeater station whereby indications transmitted from a distant field station during a particular cycle of operations leave the field stations on one half-step of the stepping mechanism and arrive 35 at the control office on the following half-step when only one repeater station is employed. When two repeater stations are employed, indications transmitted from a field station beyond the second repeater station leave such field station on one half-step of the stepping mechanism and arrive at the control office on the second 40 half-step following. This arrangement of storage and repeater station is so organized that irrespective of the number of repeater stations employed, 45 the length of the operating cycle for any given capacity remains the same, or in other words, the number of steps necessary for the stepping mechanisms for the control office and the field stations between the control office and the first 50 repeater station remain the same irrespective of the use of one or more repeater stations.

Other objects, purposes and characteristic features of the present invention will be in part obvious from the accompanying drawings and in 55

part pointed out as the description of the invention progresses.

The system of the present invention is an improvement over the repeater system disclosed in 5 the prior application of W. D. Hailes, Ser. No. 33,826, filed July 30, 1935, Patent No. 2,097,789 dated November 2, 1937.

In describing the invention in detail reference will be made to the accompanying drawings, in 10 which like reference characters designate corresponding parts, in which distinctive exponents are used at different locations and in which:

Fig. 1 is a diagrammatic illustration of the layout of a system to which the present invention 15 is particularly applicable.

Figs. 1A and 1B illustrate in a diagrammatic and conventional manner the circuit arrangement at the control office end of the communication system.

20 Fig. 2 illustrates in a diagrammatic and conventional manner the circuit arrangement at a field station located between the control office and the repeater station.

Fig. 3 illustrates in a diagrammatic and conventional manner the circuit organization at the repeater station.

Fig. 4 illustrates in a diagrammatic and conventional manner the circuit arrangement of a field station located beyond the repeater station.

30 Fig. 5 is a typical indication code table which will be used in explaining the operation of the present system.

In following the circuits of the present invention Figs. 1A, 1B, 2, 3 and 4 should be placed together in the order named with correspondingly identified lines in alignment.

40 For the purpose of simplifying the illustrations and facilitating in the explanation, the various parts and circuits constituting the embodiment of the invention have been shown diagrammatically and certain conventional illustrations have been employed, the drawings having been made more with the purpose of making it easier to understand the processes and mode of operation than with the idea of illustrating the specific construction and arrangement of parts that would be employed in practice. Thus the various relays and 45 their contacts are illustrated in a conventional manner and symbols are used to indicate connections to the terminals of batteries or other sources of electric current instead of showing all of the wiring connections to these terminals.

50 The symbols (+) and (−) are employed to indicate the positive and negative terminals respectively of suitable batteries or other sources of current and the circuits with which these symbols are used always have current flowing in the same direction, that is from (+) to (−). The symbols (B+) and (B−) are employed to indicate the positive and negative terminals respectively of a battery or other source of direct current having a mid-tap (CN) and the circuits with which these symbols are used may have current flowing in one direction or another depending 60 upon whether the circuit is connected to (B+) or (B−).

65 In the lower right hand portion of Fig. 1B relay FC is blocked in, in dotted lines. This is the same FC relay which is illustrated in the upper portion of Fig. 1A and in order to simplify the circuit connections from contact 91 of relay 2SA through contact 99 of relay FC to contact 92 of relay 2FP, the location of relay FC has been indicated in two places. It is believed however that 70 this will not be confusing in following the oper-

ation of the system especially since the operating and stick circuits of the FC relay are not shown in the present disclosure.

75 *Control office equipment.*—The control office equipment includes a neutral line relay F which repeats the impulses applied to the control line circuit, comprising control line conductor CL and control return conductor CR, from battery CB. Neutral line repeating relays FP and 2FP repeat 10 the impulses applied to relay F and since these relays are of the quick acting type they follow the operations of relay F with minimum delay. Slow acting line repeating relays SA and 2SA are for the purpose of defining the bounds of each 15 operating cycle, that is these relays are picked up at the beginning of each cycle, remain up throughout the impulsion of the cycle and are dropped at the end of the cycle.

20 Cycle determining relay C and code determining relay CD are picked up in response to the actuation of button SB at the beginning of a cycle, during which controls are transmitted. The detailed circuits for controlling the operation of relays C and CD are not shown since they are immaterial for an understanding of the present 25 invention and may be arranged as shown in detail in the prior patent to T. J. Judge and C. S. Bushnell Patent No. 2,082,544 dated June 1, 1937.

30 Field cycle determining relay FC remains down during a control cycle but is picked up during a duplex cycle or a cycle for the transmission of indications alone. The circuit arrangement of relay FC is likewise omitted from the present drawings for the sake of simplicity, but this relay 35 may be controlled in the same manner as disclosed in the above mentioned application Ser. No. 640,062.

35 Code sending relays PC and NC are for the purpose of applying (+) and (−) impulses respectively to the control line circuit during a cycle of 40 operations. Relays MB and MF are for the purpose of receiving indications during an operating cycle over the primary indication line circuit, comprising indication line conductor IL and indication return conductor IR.

45 A suitable step-by-step relay bank is employed including relays VP, 1V, 2V and LV. Relay 1V, 2V and LV pick up during the de-energized or "off" periods of the impulses in the control line circuit and relay VP shifts its position during the 50 energized or "on" periods of the impulses in the control line circuit. When the stepping relays are picked up they are stuck up until the end of the cycle. Half step relay VP is picked up and dropped during alternate "on" periods of the 55 cycle, all of which will be pointed out in detail. Control line impulsion relay E controls the application of the impulses to the primary control line circuit by opening and closing the energizing circuit of the PC and NC relays at the proper 60 times as determined by the response of the stepping relay bank in the control office to the impulses applied to the line.

65 Resistance CRS is a charging resistance for precharging the indication line circuit extending 65 from the office to the repeater station, to apply a charging current at the beginning of each interval devoted to the transmission of indications.

70 Although not shown in the present drawings, it will be understood that the control office is provided with a suitable control machine which includes a miniature track diagram representative of the actual track layout in the field. Certain control levers and buttons which are manually operable to obtain the desired control are in- 75

cluded in the control machine, switch machine lever SML and starting button SB being typical of such devices. It will be understood that a starting button is provided for each group of control levers and is associated with a particular field station, so that the positioning of the control levers for a particular station results in the transmission of controls to that station following the operation of the associated starting button. Station selection is provided by the particular CD relay which is picked up in response to the operation of a particular starting button, by connecting the PC and NC relays to the channel circuits selected by the stepping relay bank by means of code jumpers connected in various combinations for providing station selecting codes.

For the purpose of illustrating how the reception of indications on the MB and MF relays in the control office store these indications for the purpose of station registration and indicating registration, pilot relays 1PB, 1PF and 2PB are shown in Fig. 1A. Station relays 1ST and 5ST are illustrated as being typical of the registration of a transmitting field station in the control office by the selection and operation of one of these station relays during a cycle of operations. Indication storing relay 1RF is illustrated to show how an indication received from station No. 5 is transferred from the message receiving relay MF during a cycle of operations when station No. 5 is selected. Relay 1RF is of the polar magnetic stick type, that is its contacts are operated to the right and left when (B-) and (B+) respectively are connected to its winding by way of contact 96 of relay MF. It will be understood that there are other indication storing relays for receiving other indications from station No. 5 and from other stations in the system, but it is believed that the illustration of relay 1RF and an explanation of its operation will be sufficient for an understanding of the present invention.

Repeater station equipment.—It is assumed (see Fig. 1) that the present system comprises a control office connected to a repeater station by means of primary control and indication line circuits and that there are four field stations connected to these line circuits between the control office and the repeater station. It is also assumed that there are four field stations connected to the secondary control and indication line circuits which extend beyond the repeater station.

The repeater station (illustrated in Fig. 3) includes a biased to neutral polar line relay F³ and a neutral quick acting line relay 1F³. These line relays repeat the impulses applied to the primary control line circuit in the control office. The (+) and (-) impulses applied to the primary control line circuit and received by relay F³ effect the operation of relays PC³ and NC³ respectively to apply corresponding polar impulses to the secondary control line circuit, comprising control line conductor CL¹ and control return conductor CR¹ extending to the field stations beyond the repeater station. The impulses in the primary control line circuit and the impulses repeated into the secondary control line circuit are repeated (irrespective of their polarity) by neutral line relays 1F³ and FN³ respectively.

Slow acting relays S³, SA³ and SB³ are for the purpose of marking the bounds of cycles of operation, the detailed operation of these relays being explained later.

75 Relays FP³ and 2FP³ operate during a cycle, for

the repeating of indications, these relays repeating the operations of line relay FN³ as will be described in detail. Lock-out relay LO³ functions to provide a lock-out operation so that field stations located in the primary section of the communication system may obtain access to the primary line circuits for the purpose of transmitting their indications in preference to the repeater station. The detailed lock-out feature will be described later.

Resistance CRS³ corresponds to resistance CRS in the control office and is for a similar purpose, that is the secondary indication line circuit is precharged over a circuit including this resistor to apply a charging current at the beginning of each interval devoted to the transmission of indications. Indication battery IB¹ corresponds to indication battery IB in the control office and it will be understood that these batteries are for the purpose of energizing the secondary and primary indication line circuits respectively for the transmission of indications. Relays MB³ and MF³ correspond to relays MB and MF in the control office and are for the purpose of receiving indications transmitted from a field station in the secondary section. These indication receiving relays receive the registration and indication codes transmitted from a field station in the secondary section during one half step of an operating cycle and transmit the corresponding codes to the control office during a following half-step of an operating cycle.

Resistance 1R³ is a compensating resistance for compensating for the lower winding of relay LO³ which is removed from the primary indication line circuit after the lock-out period of a cycle. Resistance 2R³ is a compensating resistance to compensate for the value of resistance of the primary indication line circuit which is disconnected when the repeater station is transmitting. It will be understood that when the repeater station is located at the end of the primary section, as illustrated in Fig. 1, resistance 2R³ is not required and the terminals to which it is connected are strapped by a jumper and the resistance removed. On the other hand, if the repeater station is located at a point in the primary section with field stations connected farther out from the control office, then resistance 2R³ is provided, the value of which is determined by the resistance of the indication line circuit which is disconnected when the repeater station is transmitting.

Field station equipment.—A field station (see Fig. 2) located in the primary section is similar to a field station (see Fig. 4) located in the secondary section. Therefore the circuit arrangement of Fig. 2 is the same as the circuit arrangement of Fig. 4 except that reference characters are provided in accordance with the figure number and a different connection of the station identifying code jumpers is provided at each station. These field stations each include a biased-to-neutral polar line relay F and line repeating relays FP, SA and SB (with distinctive exponents), which relays operate in a similar manner to corresponding relays in the control office, except that the line relay is a polar relay for receiving the polar impulses in the control line circuit. Relay SB (with distinctive exponent) corresponds to relay 2SA in the control office except, as indicated in the field station drawings, this relay is not of the slow acting type.

Each field station includes a bank of stepping relays IV, 2V, LV, and the associated half step

relay VP, (with distinctive exponents) operating substantially in synchronism with corresponding relays in the control office, in response to impulses applied to the control line circuits. The 5 detailed circuit arrangement for operating the stepping relay banks and the line repeater relays have not been shown since they may be the same as for corresponding relays in the control office. It is thus believed obvious that the line 10 repeating relays and the stepping relays operate in response to the operations of relays FP² and FP⁴ by means of circuits which are not shown but merely indicated by dotted line connections 265 and 465.

15 Relays PB and PF (with distinctive exponents) are controlled locally in accordance with the local jumper connections and the positions of local relay contacts. These relays function to condition the indication line circuits in accordance 20 with indications to be transmitted during the different periods of a cycle as will be pointed out in detail.

Lock-out relays LO² and LO⁴ are picked up in response to a field start condition at the associated station and they function to close the primary indication line circuit or the secondary indication line circuit respectively, for initiating a cycle of operations for the transmission of indications from the associated station. It will be 30 understood that lock-out relay LO² locks out more distant field stations in the primary section and lock-out relay LO⁴ locks out more distant field stations in the secondary section, so that these more distant stations are ineffective to 35 obtain access to the communication system during a cycle of operations for the transmission of their indications when the illustrated stations have use of the line circuits.

Resistance units 1R² and 1R⁴ are compensating 40 resistances for compensating for the resistance of the lower winding of the associated LO relay which is removed from the indication line circuit after the lock-out period. Resistance units 2R² and 2R⁴ are compensating resistances to compensate for the value of resistance in the associated 45 indication line circuit which is disconnected when a particular field station is transmitting. When the field station of Fig. 2 is transmitting, primary indication line conductor IL is connected to return line conductor IR by way of resistance 2R², which resistance is of the proper value to compensate for the resistance of the primary indication line circuit which would be completed at the end station of a series of field stations connected to the primary indication line circuit. 50 Likewise, when the field station of Fig. 4 is transmitting, the secondary indication line conductor IL¹ is connected to return conductor IR¹ by way of resistance 2R⁴, which resistance is of the proper value to compensate for the resistance of the secondary indication line circuit which would be completed at the end station of a series of field stations connected to the secondary indication line circuit. 55

60 Track switches TS² and TS⁴ are illustrated as being controlled by switch machines SM² and SM⁴ in response to the operation of switch machine relays SMR² and SMR⁴. The occupied and unoccupied conditions of the illustrated 70 track sections are repeated by track relays T² and T⁴ in the usual manner.

75 The control of the signals at the illustrated stations has not been shown, since the control of the switch machine may be considered typical of the manner in which additional steps of the

cycle function to control signals in response to additional impulses. Change relays CH² and CH⁴ are normally energized and are dropped (circuits not shown) in response to a change in condition at the associated field station, for initiating the system into a cycle of operations for the transmission of indications. 5

The station selection portion of the system is not illustrated since this feature is immaterial for an understanding of the present invention. 10 Station selection may be provided as explained in detail in above mentioned Patent No. 2,082,544. It need only be mentioned here that station relays SO² and SO⁴ are picked up at the beginning 15 of a control or duplex cycle and remain up after the station selection steps of a cycle at the associated station only when controls are to be transmitted to this associated station.

General operation

20 For convenience in describing the operation of this system the control line circuit and the indication line circuit (see Fig. 1) extending from the control office to the repeater station will be referred to as the primary control line circuit and the primary indication line circuit respectively. The control line circuit and the indication line circuit extending from the repeater station to the distant field stations will be referred to as the secondary control line circuit and the secondary 25 indication line circuit respectively. It will be understood that the number of field stations included in the primary and secondary line circuits may be varied to suit operating conditions but the arrangement illustrated in Fig. 1 is typical. 30

The repeater station of the present invention repeats or retransmits the controls to the secondary section in straight time cascade, while the indications from the secondary section are transmitted to the repeater station on one half-step 40 of a cycle of operations and then repeated or retransmitted to the control office on the following half-step. In other words an indication from any field station in the secondary section leaves the transmitting field station on one half-step 45 and arrives at the control office on the following half-step.

From the above it will be obvious that a field station in the secondary section cannot register 50 a pulse in the control office during the first "off" period or first half-step of a cycle. It will be pointed out during the detailed description of the operation of the system that practical use is made of this inability to transmit from the secondary section into the control office during the 55 first "off" period, so that no loss of station or indication capacity will result for those stations connected to the secondary section, by deliberately assigning the station registration codes for all stations in the secondary section to start off 60 with a non-pulse on the first half-step.

As noted in Fig. 1, and for convenience in 65 describing the operation of the system, a + digit of a code is one which impulses or closes the indication line circuit, while a - digit of a code is a non-pulse or one which leaves the indication line 70 circuit open. It will be observed that the first code digit of all the stations in the secondary section begin with -. In accordance with the above discussion and as will be later pointed out, it will be apparent that this - digit (non-pulse) 75 effects the registration of this digit for stations in the secondary section during the first "off" period without the actual transmission of any code digit from the repeater station to the control office.

In the event that any one of the field stations connected to the secondary line circuit (secondary section of Fig. 1) has new indications to transmit to the control office, the transmitting field station 5 transmits these indications to the repeater station where they are received on the MB³ and MF³ relays during one half-step of the operating cycle and retransmitted to the control office in accordance with the condition of the MB³ and MF³ relays 10 during a succeeding half-step of the cycle.

The lock-out feature at the repeater station functions the same as at an ordinary field station. The repeater station is inferior to all stations connected to the primary line circuit (primary 15 section of Fig. 1), which are located nearer the control office, and the repeater station is superior to all field stations more distant from the control office. The lock-out feature at the field stations 20 is of the geographic lock-out type, that is a field station in the secondary section nearer the repeater station is superior to more distant field stations connected to the secondary line circuits and a field station in the primary section nearer the control office is superior to more distant stations 25 in that section.

One or more repeater stations may be used as required and if more than one repeater station is used in the system the controls are repeated in the same manner as illustrated in the accompanying 30 drawings without any storage feature, while the indications are first received at the repeater station associated with the line section to which the transmitting field station is connected during one half-step of the stepping mechanisms associated 35 with this section, with the received indications retransmitted from the repeater station into the next section during a following half-step of the stepping mechanisms and this is repeated as many times as there are repeater stations in the system.

40 The line circuits of a selector system such as disclosed in the above mentioned Patent No. 2,082,544 comprise a control line circuit, including control line conductor CL, control return conductor CR, and an indication line circuit including 45 indication line conductor IL and indication return conductor IR. These two line circuits correspond to the control line circuit, including conductors 10 and 12, and the indication line circuit including conductors 14 and 16 of the above mentioned prior 50 application. In a system of this character the control line conductor CL is connected to the control return conductor CR at the repeater station associated with the primary line circuit, with the line relays of any field station or stations 55 between the repeater station and the control office, as well as the line relay at the control office and at the repeater station connected in series with the primary control line wire.

60 The primary control line circuit is energized with positive and negative impulses from a control line battery in the control office for the purpose of transmitting controls and for the purpose of causing the synchronous step-by-step operation at the control office and at the primary stations, as will 65 be later explained.

The primary indication line circuit is energized from an indication line battery in the control office, having included therein at the control office, message receiving relays MF and MB which are 70 controlled through front and back contacts respectively of relays FP and 2FP, as well as through contacts of relays PC and NC, to include these message receiving relays in the indication line circuit at the proper intervals of the operating cycle. The primary indication line conductor IL

extends to all of the field stations connected to the primary line circuits and normally includes a back contact, such as back contact 256 of relay LO² of Fig. 2, at any station located between the office and the repeater station. In the present embodiment the primary indication line conductor terminates at front contact 356 of relay LO³ at the repeater station. 5

When a particular field station is transmitting, the lock-out relay at that station is picked up 10 thereby rendering the open or closed conductive condition of the primary indication line circuit with which the transmitting station is associated dependent upon the control of either a relay similar to relay PF² or PB² of Fig. 2 in accordance 15 with whether the primary control line circuit is energized or de-energized. It will be understood that the above discussion assumes that the transmitting field station is connected to the line circuits associated with the primary section. 20

A similar condition exists with regard to the secondary section, that is the secondary control line circuit includes line relays at the field stations of this section, with the secondary control line conductor CL¹ permanently connected to the 25 secondary return line conductor CR¹ at the end station. The lock-out arrangement and the condition of the secondary indication line circuit by the PB⁴ and PF⁴ relays associated with the secondary indication line circuit is similar to the 30 operation of corresponding relays associated with the primary indication line circuit, with the secondary indication line circuit normally open at the last station.

Detailed operation

35

Normal conditions.—With the system in its normal condition as indicated in the accompanying drawings, the primary control line circuit and the secondary control line circuit are both de-energized. The primary indication line circuit and the secondary indication line circuit are both normally open. All relays in the control office and at the repeater station are normally de-energized. All relays at the field stations (Figs. 2 and 4) are likewise normally de-energized, with the exception of the track relays T² and T⁴ which are illustrated in their picked up conditions since it is assumed that the associated track sections are unoccupied. Change relays CH² and CH⁴ are 50 normally energized and are likewise shown in their picked up conditions since it is assumed that no field start has been initiated. 45

For convenience in describing the operations which follow, the energized or impulse periods of the control line circuits will be referred to as "on" periods, while the de-energized periods between impulses will be referred to as "off" periods. The system will be described as stepping through cycles each comprising a conditioning "on" period, a first "off" period, a first "on" period, a second "off" period, a second "on" period and a third (clearing out) "off" period. These five distinctive periods (exclusive of the clearing out period), of an operating cycle are illustrated in the 60 code table of Fig. 5 and will be referred to later in describing the transmission of codes from stations in the primary and secondary sections. 65

Manual start.—It will first be assumed that the operator in the control office desires to move 70 track switch TS⁴ at the field station illustrated in Fig. 4 from its normal locked position to its reverse locked position. It will be assumed that the illustrated field station responds to a code combination of (+) and (-) on the first two 75

steps of the operating cycle. It will also be assumed that the track switch is operated to its reverse position in response to a (—) impulse on the third step of the cycle.

With the system in its normal condition the actuation of starting button SB in the control office is effective to pick up relays C and CD for initiating a control cycle. Since the detailed circuit arrangement for controlling the C and CD relays is immaterial for an understanding of the present invention it has been omitted from the present disclosure, but this circuit arrangement may be the same as disclosed in the above mentioned application Ser. No. 640,062. It will be understood that only one CD relay can be picked up at any one time and only at the time the system is in its normal condition.

The picking up of relays CD and C closes a circuit for picking up relay PC which extends from (+), (Figs. 1A and 1B) back contact 38 of relay E, conductor 10, front contact 41 of relay C back contacts 43 and 44 of relays 2V and 1V respectively, conductor 45, front contact 46 of relay CD, code jumper 5, PC bus 47 and winding of relay PC to (—).

Impulsing and stepping operations.—The picking up of relay PC energizes the primary control line circuit with a (+) impulse to mark the beginning of the conditioning "on" period. This impulse circuit extends from the (+) terminal of battery CB, front contact 51 of relay PC, back contact 54 of relay NC, winding of relay F, primary control line conductor CL, winding of relay F², primary control line conductor CL, windings of relays F³ and 1F³, primary control return conductor CR, back contact 50 of relay NC and front contact 53 of relay PC to the (—) terminal of battery CB.

This energization of the primary control line circuit picks up relay F in the control office and positions the polar contacts of relay F² (and similar line relays at any other stations connected to the primary control line circuit) to the right. Relay F³ at the repeater station likewise positions its polar contact 367 to the right and relay 1F³ is picked up. Relay F closes an obvious circuit at its front contact 67 for picking up relay FP, relay FP closes an obvious circuit at its front contact 68 for picking up relay 2FP, relay 2FP closes an obvious circuit at its front contact 69 for picking up relay SA and relay SA closes an obvious circuit at its front contact 70 for picking up relay 2SA.

Relay F² closes an obvious circuit at contact 267 in its right hand dotted position for picking up relay FP². The following impulses which are applied to the control line circuit effect the intermittent operation of relays F² and FP² which, by means of circuits not shown in Fig. 2, control the operations of the relays SA², SB², VP², 1V², 2V² and LV², but since these operations are similar to corresponding operations at the field station of Fig. 4, which will be pointed out later, it is believed unnecessary to complicate the discussion by including the detailed circuits of the above mentioned relays at the primary station (Fig. 2).

Relay F³ closes an obvious pick-up circuit for relay PC³ at contact 367 in its right hand dotted position. Relay PC³ closes an obvious circuit at its front contact 366 for picking up relay S³ and Relay S³ closes a circuit for picking up relay SB³, which extends from (+), front contact 370 of relay S³, back contact 381 of relay LO³ and winding of relay SB³ to (—).

The picking up of relay PC³ applies a (+) impulse to the secondary control line circuit over a circuit extending from the (+) terminal of battery CB¹, front contact 351 of relay PC³, back contact 354 of relay NC³, winding of relay FN³, secondary control line conductor CL¹ (and including other line relays at any other stations connected to the secondary control line circuit), winding of relay F⁴, secondary control return conductor CR¹, back contact 350 of relay NC³ and front contact 353 of relay PC³ to the (—) terminal of battery CB¹.

Relay FN³ is picked up in response to the energization of the secondary control line circuit and relay F⁴ actuates its polar contacts to the right. It will be understood that the line relays at the field stations interposed between the repeater station and the field station of Fig. 4 operate in response to the impulses applied to the secondary control line circuit, but since it is believed unnecessary to show the circuits of these stations, only brief mention will be made of their operation later in the description.

At the field station of Fig. 4 the actuation of contact 467 of relay F⁴ to the right closes an obvious pick-up circuit for relay FP⁴. Although the detailed circuits are not shown in Fig. 4, in accordance with the operation of the system, disclosed in the above mentioned application Ser. No. 640,062, the conditioning (+) impulse applied to the secondary control line effects the pick-up of the station relays at a portion of the field stations, such as relays SO⁴ of Fig. 4. Thus, due to the actuation of contact 414 of relay F⁴ to the right it will be assumed that relay SO⁴ is picked up and remains in its picked up condition in response to the station selecting impulses applied to the line circuits for selecting the station illustrated in Fig. 4, so that the first control impulse following station selection will be effective at the station illustrated in Fig. 4, due to closed front contact 415 of relay SO⁴.

As above mentioned, the detailed circuits for controlling relays SA⁴, SB⁴, VP⁴, 1V⁴, 2V⁴ and LV⁴ at the field station illustrated in Fig. 4 have been omitted since this control may be effected in the same manner disclosed in the above mentioned application Ser. No. 640,062 and indicated by dotted line 465.

The energization of the primary and secondary control line circuits as above described is effective to provide the conditioning "on" period of the cycle. During this "on" period, relay VP in the control office is picked up over a circuit extending from (+), front contact 71 of relay SA, front contact 72 of relay 2FP, conductor 12, back contacts 85 and 73 of relays 2V and 1V respectively and winding of relay VP to (—). Relay VP closes a first stick circuit for itself extending from (+), front contact 71 of relay SA, conductor 11, front contact 74 of relay VP, back contacts 85 and 73 of relays 2V and 1V respectively and winding of relay VP to (—). The picking up of relay 2SA (which picks up a little later than relay VP) closes an energizing circuit for relay E which extends from (+), front contact 90 of relay 2SA, conductor 13, back contacts 31 and 32 of relays 2V and 1V respectively, front contact 33 of relay VP, conductor 14 and winding of relay E to (—).

The picking up of relay E opens the energizing circuit of relay PC at back contact 38, relay PC drops and opens the primary control line circuit to mark the end of the conditioning "on" period and the beginning of the first "off" period.

This drops relays F, FP and 2FP in the control office. Relays F³, 1F³ and PC³ at the repeater station are de-energized, the dropping of relay PC³ de-energizing the secondary control line circuit which is effective to drop relays F⁴ and FP⁴ at the field station. Relay FN³ is likewise de-energized in response to the de-energization of the secondary control line circuit, but since this relay is ineffective during a control cycle its operation will not further be mentioned during the description of the control cycle operation. It need only be mentioned that relay FN³ responds to the impulses applied to the secondary control line circuit.

15 The dropping of relay 2FP in the control office closes a circuit for picking up relay 1V which extends from (+), front contact 75 of relay SA, back contact 76 of relay 2FP, conductor 15, front contact 77 of relay VP, back contact 78 of relay 2V and winding of relay 1V to (-). Relay 1V closes a stick circuit for itself extending from (+), front contact 75 of relay SA, conductor 16, front contact 79 and winding of relay 1V to (-). This stick circuit for relay 1V is maintained energized until relay SA is dropped at the end of the cycle. It will be obvious that relays 2V and LV, when picked up, close similar stick circuits for themselves at their front contacts 83 and 84 respectively and it will not be necessary to 30 point out the closure of these stick circuits again during the operation of the system, since they are likewise maintained energized until the end of the cycle.

35 The picking up of relay 1V opens the first stick circuit of relay VP at back contact 73, but prior to this a second stick circuit is closed for relay VP which extends from (+), front contact 71 of relay SA, back contact 72 of relay 2FP, conductor 17, front contact 80 and winding of relay 40 VP to (-).

45 The picking up of relay 1V de-energizes relay E at back contact 32 and the dropping of relay E picks up relay NC over a circuit extending from (+), back contact 33 of relay E, conductor 19, front contact 41 of relay C, back contact 43 of relay 2V, front contact 44 of relay 1V, conductor 56, front contact 57 of relay CD, code jumper 6, NC bus 48 and winding of relay NC to (-).

50 The primary control line circuit is now energized with a (-) impulse to mark the end of the first "off" period and the beginning of the first "on" period. This circuit extends from battery CB, through back contacts 51 and 53 of relay PC and front contacts 50 and 54 of relay NC, which contacts reverse the connection of the 55 battery applied to the primary control line circuit from that previously pointed out.

55 The (-) energization of the primary control line circuit effects the picking up of relays F, FP and 2FP in the control office, positioning of the polar contacts of relay F³ at the repeater station to the left, the picking up of relay 1F³ and the picking up of relay NC³ over an obvious circuit closed at contact 361 of relay F³ in its left hand dotted position. With relay NC³ picked up and relay PC³ down, the secondary control line circuit is energized with a (-) impulse over a circuit which includes contacts 351 and 353 of relay PC³ and contacts 350 and 354 of relay NC³ 70 in positions reversed from that previously described.

75 The picking up of relay 2FP in the control office drops relay VP because its first stick circuit is open at back contact 73 of relay 1V and its second stick circuit is open at back contact

72 of relay 2FP. The dropping of relay VP closes a circuit for picking up relay E which extends from (+), front contact 90 of relay 2SA, conductor 13, back contact 31 of relay 2V, front contact 32 of relay 1V, back contact 33 of relay VP, 5 conductor 14 and winding of relay E to (-).

The picking up of relay E de-energizes the above traced circuit for relay NC, which drops and de-energizes the primary control line circuit to mark the end of the first "on" period and the 10 beginning of the second "off" period. Relays F, FP and 2FP are dropped and relay 2V is picked up over a circuit extending from (+), front contact 75 of relay SA, back contact 76 of relay 2FP, conductor 15, back contact 77 of relay VP, 15 front contact 82 of relay 1V and winding of relay 2V to (-). The picking up of relay 2V de-energizes relay E at open back contact 31 and the dropping of relay E energizes relay NC, which in turn energizes the primary control line circuit 20 to mark the end of the second "off" period and the beginning of the second "on" period.

Relays F, FP, and 2FP are picked up in response to the energization of the primary control line circuit at the beginning of the second "on" period. Relay VP is picked up over a circuit extending from (+), front contact 71 of relay SA, front contact 72 of relay 2FP, conductor 12, front contact 85 of relay 2V and winding of relay VP to (-). Relay VP again completes and 25 prepares its stick circuits which are believed to be obvious and unnecessary to be pointed out again. The picking up of relay VP energizes relay E over a circuit extending from (+), front contact 90 of relay 2SA, conductor 13, front contacts 31 and 35 33 of relays 2V and VP respectively, conductor 14 and winding of relay E to (-).

The picking up of relay E de-energizes relay NC at back contact 38 and relay NC drops to de-energize the primary control line circuit to mark 40 the end of the second "on" period and the beginning of the third or clearing out "off" period. Relays F, FP and 2FP are dropped and relay LV is picked up over a circuit extending from (+), front contact 75 of relay SA, back contact 76 of relay 2FP, conductor 15, front contacts 77 and 78 of relays VP and 2V respectively and winding of relay LV to (-).

The picking up of relay LV does not change the circuit condition of relay E and it remains 50 up, the PC and NC relays remain down and the primary control line circuit remains de-energized so that relay 2FP remains down for a sufficiently long period to drop relays SA and 2SA for clearing out the circuits. The dropping 55 of relays SA and 2SA de-energize relays E, VP, 1V, 2V and LV by the opening of front contacts 90, 71 and 75. The dropping of relay SA also de-energizes relays CD and C by circuits not shown in the present disclosure. 60

When relay 2V was picked up during the second "off" period as above described, its contact 43 shifted the energizing circuit from conductor 56 to 61, which extends this circuit through front contact 62 of relay CD, lever SML in its left 65 hand dotted line position (reverse) and NC bus 48 to the winding of relay NC. This is effective to apply a (-) impulse to the control line circuit during the second "on" period. It will be understood that lever SML in its full line (normal) position would energize relay PC instead of relay NC, so that the switch control impulse would be (+) instead of (-).

Referring to the field station illustrated in Fig. 4, it will be recalled that the (+) and (-) im- 75

pulses applied to the primary control line circuit are repeated into the secondary control line circuit by the operations of relays PC³ and NC³ respectively at the repeater station. It will be understood that the conditioning and the first impulses, which were assumed to be (+) and (—) because of the connections of jumpers 5 and 6 in the control office, were effective to select the station illustrated in Fig. 4 by maintaining relay SO⁴ in its energized condition.

After the station is selected the next impulse (second "on"), which was (—) applied to the secondary control line circuit in response to the (—) impulse applied to the primary control line circuit (because lever SML was assumed to be in its reverse position), positions contact 414 of relay F⁴ to the left. This closes a circuit for energizing relay SMR⁴ extending from (CN), winding of relay SMR⁴, front contact 416 of relay 2V⁴, front contact 415 of relay SO⁴ and contact 414 of relay F⁴ in its left hand dotted position to (B—). This positions contact 450 of relay SMR⁴ to its left hand dotted position for controlling the operation of the switch machine SM⁴ for actuating track switch TS⁴ to its reverse locked position.

It will be apparent that a (+) impulse received at the field station of Fig. 4 during the second "on" period would position contact 414 of relay F⁴ to the right, which would energize relay SMR⁴ in the opposite direction for positioning contact 450 to the right for operating the switch machine and track switch to its normal locked position.

It will be understood that relays F², FP², F⁴ and FP⁴ which follow the impulses in the primary and secondary control line circuits remain de-energized at the end of the cycle for dropping relays SA², SB², SA⁴, SB⁴, the stepping relays at the associated stations and relays SO² and SO⁴. Likewise relays S³ and SB³ at the repeater station are dropped during the clearing out period because contacts 365 and 366 of relays NC³ and PC³ respectively remain in their dropped away positions for a comparatively long interval of time when the primary control line circuit is de-energized at the end of the cycle.

Indications

It will be pointed out in the description which follows how the system is initiated from the field station of Fig. 4 which is located in the secondary section and how indications are transmitted from this station, received at the repeater station and retransmitted to the control office. Although the circuits of a primary field station (Fig. 2) are shown somewhat in detail it is believed unnecessary to describe the initiation of the system and the transmission of indications from this station, since this portion of the operation of the system is immaterial to an understanding of the present invention and furthermore this operation has been clearly described in the above mentioned prior application 640,062. Also, it is believed that the transmission of indications from the Fig. 4 station by the conditioning of the PB⁴ and PF⁴ relays and the reception of these indications by the MB³ and MF³ relays at the repeater station are sufficiently analogous to the transmission of indications by the PB² and PF² relays of Fig. 2 and the reception of these indications on the MB and MF relays in the control office. It will be pointed out in the description which follows how the indications which are received and stored by the MF³ and MB³

relays at the repeater station are transmitted to the control office.

Automatic start.—Assuming the system to be in its normal condition when a change in condition occurs at the field station illustrated in Fig. 4, relay CH⁴ is dropped in response to such a change in condition. This closes a circuit for picking up relay LO⁴ which extends from (+), back contact 407 of relay FP⁴, back contact 438 of relay SB⁴, back contact 453 of relay SA⁴, upper winding of relay LO⁴ and back contact 454 of relay CH⁴.

The secondary indication line circuit is energized, in response to the picking up of relay LO⁴, over a circuit extending from the (+) terminal of battery IB¹ (Fig. 3), upper winding of relay MF³, back contact 362 of relay 1F³, back contact 396 of relay SB³, secondary indication line IL¹, front contact 456 of relay LO⁴, back contact 472 of relay SB⁴, lower winding of relay LO⁴, resistance 2R⁴ and secondary indication line return conductor IR¹ to the (—) terminal of battery IB¹.

Relay MF³ is picked up over the above described circuit and a circuit is closed for picking up relay LO³ which extends from (+), back contact 310 of relay S³, back contact 388 of relay 1F³, front contact 387 of relay MF³, back contact 358 of relay SA³ and upper winding of relay LO³ to (—).

The picking up of relay LO³ energizes the primary indication line circuit over a circuit which may be traced from the (+) terminal of battery IB (Fig. 1B), lower winding of relay MB, back contact 91 of relay 2SA, primary indication line conductor IL, back contact 256 of relay LO², indication line conductor IL, front contact 356 of relay LO³, back contact 372 of relay SB³, back contact 375 of relay FP³, lower winding of relay LO³, resistance 2R³ and secondary indication return conductor IR to the (—) terminal of battery IB.

The closing of the primary indication line circuit picks up relay MB which in turn closes a circuit for picking up relay FC at its front contact 34. The pick-up and stick circuits for relay FC have been omitted from the drawings for the sake of simplicity, since the detailed operation of this relay is immaterial for an understanding of the present invention, it being understood that the circuits for controlling relay FC can be the same as disclosed in the above mentioned application Ser. No. 640,062.

Relay NC is energized, in response to the picking up of relay FC, over a circuit extending from (+), back contact 38 of relay E, conductor 10, back contact 41 of relay C, front contact 35 of relay FC, NC bus 48 and winding of relay NC to (—). The energization of relay NC applies a conditioning (—) impulse to the primary control line circuit over the previously described circuit including front contacts 50 and 54 of relay NC. It will be assumed that this is a cycle for the transmission of indications alone (not a duplex cycle), so that relay C remains down and relay FC remains picked up for intermittently energizing relay NC by the intermittent operation of contact 38 of relay E as previously described. This provides a series of (—) impulses applied to the primary control line circuit and these impulses effect the operation of the line relay, the line repeater relays, the stepping relays and relay E in the same manner as described in connection with a control cycle.

It is believed unnecessary to point out in detail how the step-by-step operations in the control office and at the field stations are effected, since these operations are the same as already described 5 in connection with a control cycle, with the above mentioned exception that the primary control line circuit is energized with a series of (—) impulses. This positions the polar contacts of relay F^3 at the repeater station to the left for each impulse, 10 which picks up relay NC^3 to repeat a series of (—) impulses into the secondary control line circuit.

Relays F^3 , FP^3 , NC^3 , S^3 and FN^3 all operate in response to this series of (—) impulses in the manner previously explained. Since relay LO^3 15 is picked up during this indication cycle, relay SA^3 is energized in response to the picking up of relay FN^3 over a circuit extending from (+), front contact 382 of relay LO^3 , front contact 384 20 of relay FN^3 and winding of relay SA^3 to (—). Relay SA^3 being slow acting remains up during the impulsive operations until relay FN^3 is dropped at the end of the cycle for a sufficiently long period to effect the dropping of relay SA^3 .

Relay FP^3 is picked up during the conditioning 25 "on" period over a circuit extending from (+), front contact 382 of relay LO^3 , front contact 383 of relay FN^3 , front contact 385 of relay SA^3 and winding of relay FP^3 to (—). Since contacts 382 30 and 385 of relays LO^3 and SA^3 respectively remain up during this cycle, the intermittent operation of relay FN^3 is repeated by relay FP^3 because of the intermittent opening and closure of front contact 383.

Relay $2FP^3$ repeats the operations of relay FP^3 35 by contact 378 intermittently opening the energizing circuit for relay $2FP^3$ which extends from (+), front contact 382 of relay LO^3 and front contact 378 of relay FP^3 to the winding of relay $2FP^3$. Relay SE^3 is picked up during the conditioning "on" period over a circuit extending from (+), front contact 380 of relay $2FP^3$, front contact 381 of relay LO^3 and winding of relay SB^3 to (—). Relay SB^3 is stuck up throughout this cycle over a circuit extending from (+), front contact 45. 40 371 of relay SA^3 , front contact 374 and winding of relay SB^3 to (—).

Relay MB in the control office, which was picked up to initiate the cycle, remains energized over the above described circuit including 50 the primary indication line circuit, by way of its lower winding and when relay $2SA$ is picked up during the conditioning "on" period a stick circuit is completed for relay MB which extends from (+), front contact 66 of relay $2SA$, front contact 55 60 of relay $2FP$, front contact 64 and upper winding of relay MB to (—). This stick circuit is effective until relay $2FP$ is dropped during the first "off" period, when relay MB is de-energized because the primary indication line circuit is not 60 closed during this period and because the above described stick circuit is open at front contact 39 of relay $2FP$.

It will be recalled that relay E is picked up throughout each "off" period so that the 65 stick circuit for the upper winding of relay MB is also opened at back contact 65 of relay E . It will thus be seen that relay MB acts as a start relay, after which it is dropped or not during the first "off" period as determined by the first 70 "off" indication received in the primary indication line circuit being non-pulse or pulse respectively.

The first conditioning (—) impulse applied to the primary control line circuit effects the 75 operation of the line and line repeater relays at

the stations in the primary section, but since this is assumed to be a cycle for the transmission of indications alone these impulses are ineffective to select a primary station for controls. Likewise, since these primary impulses repeat a series of similar (—) impulses in the secondary line circuit no station in the secondary section is selected for controls.

It will be recalled that relay MF^3 at the repeater station was picked up in response to the 10 energization of the secondary indication line circuit to initiate the cycle. Relay MF^3 is maintained energized by current flowing over the secondary indication line circuit in series with its lower winding until the secondary indication line 15 circuit is opened at the transmitting field station by the opening of back contact 472 of relay SB^4 . The closure of front contact 472 is ineffective to close the secondary indication line circuit because the circuit through front contact 20 473 of relay FP^4 is open at front contact 499 of relay PF^4 . Thus relay MF^3 is dropped during the conditioning "on" period in preparation for its energization or de-energization during succeeding "on" periods for the reception 25 of "on" indications from the transmitting field station.

When relay LO^3 at the repeater station is picked up in response to the operation of relay MF^3 , it is maintained energized by way of its 30 lower winding until relay SA^3 is picked up to complete a stick circuit for relay LO^3 which extends from (+), front contact 368 of relay LO^3 , front contact 358 of relay SA^3 and upper winding of relay LO^3 to (—). Relay LO^4 at the transmitting station is stuck up after the operation 35 of relay SA^4 over a circuit extending from (+), front contact 468 of relay LO^4 , front contact 453 of relay SA^4 , upper winding and front contact 455 of relay LO^4 to (—). The lock-out 40 operations in the primary and secondary sections will be described later.

Transmission of indications from secondary section.—Referring to the layout of Fig. 1, it will be observed that the station registration 45 codes of all stations in the secondary section begin with a —. As indicated by the note in Fig. 1, a — symbol refers to the condition of a non-pulse in the indication line circuit and a + symbol refers to a pulse in the indication line 50 circuit. It will likewise be noted that the registration codes associated with the stations in the primary section begin with a +.

In the description which follows it will be explained how four digits of code are received in 55 the control office with only three digits of code transmitted from station No. 5 in the secondary section. Referring to the upper left hand portion of the typical indication code table of Fig. 5, it will be assumed that code No. 5, which is 60 associated with station No. 5, is received in the control office in response to station No. 5 initiating an indication cycle. Referring to the lower right hand section of Fig. 5 it will be observed that station No. 5 transmits only two 65 digits of station registration code with the third digit (2nd off) being used for the transmission of an indication from the registered station. It will also be observed that the second and third digits of the No. 5 station registration code are 70 transmitted in the first "off" and first "on" periods respectively and that these digits are received in the control office in the first "on" and the second "off" periods respectively. As will be later pointed out the first digit of the No. 5 75

station registration code is not transmitted but is registered during the first "off" period of the cycle to complete the code $-\cdot\cdot$ which is associated with station No. 5.

5 The same discussion applies to other stations in the secondary section, that is, since the code for each of these stations begins with a $-$ it is not transmitted but in effect it is registered in the control office during the first "off" period.

10 This is possible since for any given size of registration unit, one-half of the total registration codes necessarily start off with a $-$ or non-pulse, and whether this non-pulse is the result of a deliberate choice or the result of the inability of the 15 field station to pulse the indication circuit on the first half-step is immaterial in-so-far as the correct registration of the station in the office is concerned.

In other words, the first code element for each 20 of the field stations in the secondary indication line circuit requires a non-pulse and this non-pulse is represented in the code table of Fig. 5 showing the codes transmitted from the repeater station as indicated by the minuses for the first 25 "off" period. As the repeater station has not received a pulse element for distant field stations, it then transmits for such "off" period a non-pulse code element and this non-pulse code element is transmitted because of the open condition 30 of contact 391 of relay MF³ in the same sense that a non-pulse is transmitted by any of the relays PF for the field stations shown in Figs. 2 and 4.

To put it still another way, the non-pulse or 35 the first code element for each of the field stations in the secondary indication line circuit, requires no operation on the part of the field station or on the part of the repeater station. But the repeater station is effective to produce a non-pulse condition on this first time period 40 which is allotted on the primary indication line circuit for the existence of a code element condition, and on the same time period, a code element is transmitted to the repeater station over 45 the secondary indication line circuit by a pulse or a non-pulse condition which can be stored for transmission on the second time period for the primary indication line circuit. This arrangement provides, that although the actual 50 effect of a distant field station which is repeated through a repeater station is delayed a half-step, such delay does not result in the requirement of added steps by reason of the manner in which the station selecting codes are arbitrarily chosen 55 in accordance with the principles of the present invention.

From the above it follows that for any given 60 size of registration unit one-fourth of the total registration codes start off with two-non-pulses and these can be used in a succeeding third section with no loss of capacity. Likewise one-eighth of the total registration codes (in a system of the proper size) start off with three non-pulses and these codes can be used in a succeeding 65 fourth section with no loss of capacity.

Thus, it is seen that for each of the non-pulse 70 code elements for the stations beyond a repeater station, a non-pulse code element condition is set up in the indication line circuit extending from such repeater station by that particular repeater station. For example, if there are three repeater stations, the first repeater station from the control office will condition the primary indication line circuit with three non-pulse conditions; the second repeater station will condition

the second indication line circuit with two non-pulse conditions and the third repeater station will condition the third indication line circuit with one non-pulse condition. These non-pulse code elements occur automatically and the corresponding step periods at the field station transmitting can be used to transmit the code elements from that station on which there is a possibility of a pulse condition occurring and when such pulse code elements do occur they are 10 relayed on through the repeater stations so as to arrive at the control office upon the right half-step period because of the intervening non-pulse code elements having been automatically impressed upon the primary indication line circuit. 15

During an indication cycle, indications are transmitted from a secondary field station, illustrated in Fig. 4 for example, to the repeater station illustrated in Fig. 3 by the conditioning of the secondary indication line circuit. Relays LO⁴ and SB⁴ remain picked up at the transmitting field station throughout the indication cycle so that the circuit of the secondary indication line, including front contact 472 of relay SB⁴, can be opened or closed during both the 20 "on" and "off" periods as selected by contact 473 of relay FP⁴ in accordance with the closed or open conditions of contacts 499 and 491 of relays PF⁴ and PB⁴ respectively.

During each "off" period in the series of impulses the (+) terminal of indication battery IB¹ (Fig. 3) is connected to secondary indication line conductor IL¹ through the upper winding of relay MB³ and current flow in the secondary indication line circuit is dependent upon 30 front contact 491 of relay PB⁴ being closed. More specifically, relay PB⁴ is the code transmitter for the "off" periods of the impulses in the secondary line circuit. Assuming jumper 480 at the transmitting secondary station (illustrated in 40 Fig. 4) to be connected to (+) as shown, relay PB⁴ is picked up during the conditioning "on" period over a circuit extending from (+), jumper 480, back contacts 485 and 486 of relays 1V⁴ and 2V⁴ respectively, front contact 488 of relay 45 FP⁴, winding of relay PB⁴ and front contact 489 of relay LO⁴ to (-). The picking up of relay PE⁴ provides one of a choice of two "off" indications.

When relay FP⁴ is dropped during the first 50 "off" period, relay PB⁴ is stuck up over a circuit extending from (+), front contact 490 of relay PB⁴, back contact 488 of relay FP⁴, winding of relay PB⁴ and front contact 489 of relay LO⁴ to (-). When relay FP⁴ is picked up during the 55 first "on" period the above described stick circuit is opened and the energization of relay PB⁴ is dependent upon a circuit extending through front contact 485 of relay 1V⁴ for the second "off" indication, to contact 492 of relay T⁴, which being open illustrates the alternate choice of an "off" indication. Relay PB⁴ will be de-energized to transmit this alternate choice "off" indication.

With relay PB⁴ picked up during the conditioning "on" period and stuck up throughout the first 65 "off" period as above described, the secondary indication line circuit is closed as will be presently pointed out. This indication line circuit was opened during the conditioning "on" period when relay SB⁴ opened its back contact 472. 70

The lock-out period for maintaining relay LO⁴ energized extends from the time of the picking up of relay FP⁴ and the consequent opening of its back contact 407 until the picking up of relay SA⁴ and the consequent closing of its front 75

contact 453, during which period relay LO⁴ is dependent for its energization on line current received from battery IB¹, at the repeater station, through its lower winding. In the event that some other station superior to the station of Fig. 4 (in the event that the Fig. 4 station is not the station nearest the repeater station) opens the secondary indication line circuit during this lock-out period, then of course relay LO⁴ is dropped and it cannot be picked up again until the start of another cycle. With relay LO⁴ maintained picked up during the lock-out period, then when relay SA⁴ closes its front contact 453, relay LO⁴ is stuck up over a circuit including its upper winding and its front contacts 455 and 468 in series with front contact 453 of relay SA⁴. Thus relay LO⁴ is maintained picked up until relay SA⁴ drops at the end of the cycle.

During each "on" period the secondary indication line circuit remains open or is closed depending upon contact 499 of relay PF⁴. For example assuming that code jumper 482 is connected to (+) as shown in Fig. 4, relay PF⁴ is picked up during the first "off" period over a circuit extending from (+), jumper 482, back contact 494 of relay 2V⁴, front contact 496 of relay VP⁴, back contact 497 of relay FP⁴, winding of relay PF⁴ and front contact 489 of relay LO⁴ to (-). When relay FP⁴ is picked up during the first "on" period, relay PF⁴ is stuck up over a circuit extending from (+), front contact 498 of relay PF⁴, front contact 497 of relay FP⁴, winding of relay PF⁴ and front contact 489 of relay LO⁴ to (-). The above illustrates one choice of an "on" indication whereby relay PF⁴ is picked up. The other choice "on" indication is effected by the de-energization of the circuit including the winding of relay PF⁴ and back contact 497 of relay FP⁴. The second choice "on" indication de-energizes relay PF⁴ in the second "off" period so that relay PF⁴ is down throughout the second "on" period.

It will now be explained how the conditioning of relays PB⁴ and PF⁴ effect the closing and the opening of the secondary indication line circuit for transmitting indications to the repeater station where they are received, stored and retransmitted to the office.

From the above discussion of the conditioning of the PB⁴ and PF⁴ relays it will be observed that relay FP⁴ is positioned during an "off" period in accordance with the indication it is to transmit in the next "on" period, while relay PB⁴ is positioned during an "on" period in accordance with the indication it is to transmit in the next "off" period. Thus on each step taken by the step-by-step mechanism at the field station, relays PF⁴ and PB⁴ govern the secondary indication line circuit.

As will be later pointed out an indication code which is started from the station in the secondary section during the first "off" period is not received in the control office until the next or first "on" period. Therefore the code digit 2+, illustrated in the lower right hand section of Fig. 5 as being the first code transmitted from station No. 5, is received in the control office as the second code digit for station No. 5 as is indicated in the upper left hand portion of the indication code table of Fig. 5. Therefore code jumper 499 conditions relay PB⁴ to transmit the second digit of the code associated with station No. 5. It will be later explained how the first digit of the code, that is a non-pulse, registers itself in the con-

trol office to complete the station registration code.

It will be recalled that the secondary indication line circuit was opened during the conditioning "on" period by the picking up of relay SB⁴ and the consequent opening of its back contact 472. The dropping of relay 2FP³ at the repeater station during the first "off" period permits current to flow in the secondary indication line circuit because relay PB⁴ is picked up throughout this first "off" period. The circuit for this current flow may be traced from the (+) terminal of battery IB¹, upper winding of relay MB³, back contact 397 of relay FN³, back contact 394 of relay FP³, back contact 392 of relay 2FP³, front contact 390 of relay LO³, front contact 396 of relay SB³, secondary indication line conductor IL¹, front contacts 456 and 472 of relays LO⁴ and SB⁴ respectively, back contact 473 of relay FP⁴, front contact 491 of relay PB⁴, resistances 1R⁴ and 2R⁴ in series and indication return conductor IR¹ to the (-) terminal of battery IB¹.

This energization of the secondary indication line picks up relay MB³ to register the first digit of the code transmitted from station No. 5 which is actually the second digit of the station registration code. Relay MB³ is maintained picked up by current in the secondary indication line circuit until relay 1F³ picks up to close a stick circuit for relay MB³ which extends from (+), front contact 361 of relay SB³, front contact 360 of relay 1F³, front contact 364 and lower winding of relay MB³ to (-). Relay MB³ is thus stuck up throughout the "on" period, following the "off" period during which it was picked up. Relay MB³ is dropped when relay 1F³ drops and opens the above described stick circuit at front contact 360.

The picking up of relay FN³ at the repeater station at the beginning of the first "on" period opens the secondary indication line circuit at back contact 397. This de-energizes the secondary indication line circuit and when relay 2FP³ is picked up during the first "on" period the secondary indication line circuit is again energized because relay PF⁴ at the field station is picked up.

The energizing circuit for the secondary indication line extends from the (+) terminal of battery IB¹, upper winding of relay MF³, front contact 398 of relay FN³, front contact 393 of relay FP³, front contact 392 of relay 2FP³, front contact 399 of relay LO³, front contact 396 of relay SB³, secondary indication line conductor IL¹, front contacts 456 and 472 of relays LO⁴ and SB⁴ respectively, front contact 473 of relay FP⁴, front contact 499 of relay PF⁴, resistances 1R⁴ and 2R⁴ in series and indication return conductor IR¹ to the (-) terminal of battery IB¹. This effects the picking up of relay MF³, which relay is maintained energized through its upper winding until relay 1F³ drops to complete the stick circuit extending from (+), front contact 361 of relay SB³, back contact 360 of relay 1F³, front contact 363 and lower winding of relay MF³ to (-). It will thus be observed that relay MF³ when picked up during an "on" period is stuck up throughout the following "off" period.

The dropping of relay 2FP³ during the second "off" period fails to close the secondary indication line circuit because of open front contact 491 of relay PB⁴. When relay 2FP³ is picked up during the second "on" period the secondary indication line circuit is not closed because of open front contact 499 of relay PF⁴, which relay is down.

during this "on" period. It is believed unnecessary to trace the circuit for the secondary indication line since the energized and de-energized conditions of this line have been pointed out in the above typical examples.

Since the secondary indication line circuit is not energized during the second "off" period, relay MB^3 is dropped during this period when relay $1F^3$ drops and opens its front contact 360. 10 Relay MF^3 which was picked up during the first "on" period is dropped at the end of the second "off" period when relay $1F^3$ picks up and opens back contact 360.

From the above it will be observed that relay 15 MB^3 is selectively responsive during the "off" periods to the energization and de-energization of the secondary indication line circuit for receiving either one of a choice of two distinctive indications, with the selected choice maintained throughout 20 the following "on" period of relay MB^3 either being up or down throughout this "on" period. Similarly, relay MF^3 is selectively responsive during each "on" period in accordance with one or another choice of two indications transmitted 25 during each "on" period, with relay MF^3 remaining up or down throughout the following "off" period to register the selected indication which was transmitted and received by this relay.

It will be recalled that relay PB^4 was dropped 30 during the first "on" period after transmitting the first "off" code digit which was a + (pulse). Relay PB^4 is then in condition to be picked up to transmit an indication during the second "off" period in accordance with the condition of track 35 relay T^4 for example. With relay T^4 energized, as illustrated in Fig. 4, relay PB^4 will not be picked up during the first "on" period. This effects the transmission of a - (non-pulse) code digit during the second "off" period. On the other hand, 40 if relay T^4 is down, then a circuit is completed through back contact 492 for picking up relay PB^4 during the first "on" period for transmitting a + (pulse) code digit during the second "off" period. This is illustrated in the fifth column of the lower right hand section of Fig. 5 by 45 the code digit associated with the second "off" period being indicated 4+ or 4- which are the codes transmitted by relay T^4 being down or up respectively.

Transmission of indications to control office.— 50 The above explanation points out how three code digits (see lower right hand section of Fig. 5 table) are transmitted from a secondary field station during the first "off", first "on" and second "off" 55 periods and received at the repeater station during the corresponding periods. It will now be explained how these three code digits which were received and stored on relays MB^3 and MF^3 are retransmitted over the primary indication line 60 circuit during the first "on", second "off" and second "on" periods respectively.

It will be recalled that the primary indication line circuit was energized with a start pulse by the picking up of relay LO^3 to initiate the cycle. 65 The primary indication line circuit is de-energized during the conditioning "on" period when relay FP^3 at the repeater station picks up and opens its back contact 375. The closure of front contact 372 of relay SB^3 does not energize the 70 primary indication line circuit because of open front contact 399 of relay MB^3 .

During the first "off" period, battery IB (see Fig. 1B) is connected to the primary indication line circuit through the lower winding of relay 75 MB and current flow in the primary indication

line circuit is dependent upon front contact 391 of relay MF^3 . It will be recalled that relay MF^3 receives the "on" indications from the station in the secondary section and since the first "on" indication has not yet been transmitted to the 5 repeater station, relay MF^3 is down during the first "off" period and therefore the primary indication line closure cannot be completed. Likewise relay MB^3 which receives "off" indications from the transmitting station in the secondary 10 section transmits these "off" indications to the office during the succeeding "on" periods. Therefore the control office can not complete the closure of the primary indication line circuit during an indication cycle when indications are being transmitted from a station in the secondary section. This means that a - (non-pulse) will 15 always be received during the first "off" period in the control office when a station in the secondary section is transmitting.

Relay MB in the control office is therefore the code receiver for "on" indications transmitted from the secondary section and relay MF is the code receiver for "off" indications transmitted from the secondary section. Relay MB is the code receiver for "off" indications transmitted from the primary section and relay MF is the code receiver for "on" indications transmitted from the primary section. Since these indications transmitted from the primary section effect the operation of relay MB and MF in the same manner as the transmission of indications in the secondary section effect the conditioning of relay MB^3 and MF^3 as previously described, it is believed unnecessary to point out how indications are transmitted from a station in the primary section.

Referring back to the picking up of lock-out relay LO^3 at the repeater station, it will be understood that the lock-out period for maintaining relay LO^3 energized extends from the time of the 40 picking up of relay $1F^3$ and the consequent opening of its back contact 388 until the picking up of relay SA^3 and the consequent closure of its front contact 358, during which period relay LO^3 is dependent for its energization on line current received from battery IB in the control office and through its lower winding. In the event that some station in the primary section (which is superior to the repeater station) opens the primary indication line circuit during this lock-out period, then relay LO^3 is dropped and it cannot be picked up again until the start of another cycle. With relay LO^3 maintained 50 picked up during the lock-out period, then when relay SA^3 closes its front contact 358, relay LO^3 55 is stuck up over a circuit including its upper winding and its front contact 368 in series with front contact 358 of relay SA^3 . Thus relay LO^3 is maintained picked up until relay SA^3 drops at the end of the cycle.

It will be recalled that the lock-out period for stations in the secondary section extends from the time that relay FP^4 is picked up until the time that relay SA^4 is picked up. Since this period overlaps the lock-out period of the repeater station it will be obvious that a station in the secondary section which initiates the system into an indication cycle can be ruled out during its lock-out period in the event that a station in the primary section takes the line and opens the primary 70 indication line circuit back towards the repeater station.

Recalling that the primary indication line circuit cannot be pulsed during the first "off" period by a station in the secondary section, this non- 75

pulse or — code digit effects the dropping of relay MB during the first "off" period, which relay was picked up to initiate the system. With relay MB down the first code digit, which is —, is 5 executed during the first "on" period with front contact 81 of relay FP closed. This executing circuit extends from (B—), back contact 97 of relay MB, front contact 81 of relay FP, conductor 18, front contact 31 of relay FC, back contact 55 10 of relay 2V, front contact 58 of relay 1V, conductor 40 and upper winding of relay 1PB to (B—). Since (B—) is connected to both terminals of the upper winding of relay 1PB this relay remains down to register the first code digit as 15 being — or non-pulse. Since it was previously pointed out that no station in the secondary section can transmit a + or pulse code digit which is received in the control office during the first "off" period, it will be evident that no station in the 20 secondary section can pick up relay 1PB.

The second code digit is received in the control office during the first "on" period and is the code digit which was transmitted from the field station in the secondary section during the first "off" 25 period. It will be recalled that this code digit picked up relay MB³ at the repeater station and maintained it picked up throughout the first "on" period. The primary indication line circuit is therefore energized during the first "on" period 30 when relay 2FP picks up and closes its front contact 92 and until relay NC drops and opens its front contact 20. This is because relay MB³ was maintained in its picked up position throughout the first "on" period so that the primary indication line circuit is energized over a circuit extending from the (+) terminal of battery IB, lower winding of relay MF, back contact 22 of relay PC, front contact 20 of relay NC, front contact 93 of relay FP, front contact 92 of relay 2FP, front contact 35 40 of relay FC, front contact 91 of relay 2SA, indication line conductor IL, back contact 256 of relay LO², indication line conductor IL, front contact 356 of relay LO³, front contact 372 of relay SB³, front contact 373 of relay 1F³, front contact 45 55 of relay MB³, resistance units 1R³ and 2R³ in series and indication return conductor IR to the (—) terminal of battery IB.

Relay MF is picked up over the above described circuit and is held up by current flowing over the 50 primary indication line circuit until relay E is picked up to mark the beginning of the second "off" period, when a stick circuit is closed for relay MF which extends from (+), front contact 66 of relay 2SA, front contact 65 of relay E, front contact 55 60 63 and upper winding of relay MF to (—). When relay E drops to mark the end of the second "off" period the stick circuit for relay MF is maintained complete at back contact 68 of relay 2FP so that relay MF is not dropped until relay 65 70 80 FP picks up during the second "on" period while relay E is down. Therefore relay MF is maintained picked up throughout the second "off" period to execute the second code digit by means of an executing circuit which extends from (B+), front contact 96 of relay MF, back contact 86 of relay FP, conductor 9, front contact 87 of relay FC, back contact 88 of relay VP, front contact 89 of relay 1V, conductor 49 and upper winding of relay 1PF to (B—).

70 Relay 1PF is picked up, and stuck up until the end of the cycle over its stick circuit which extends from (+), front contact 59 of relay SA, conductor 42, front contact 52 and lower winding of relay 1PF to (—). The primary indication line circuit is de-energized at the end of the first

"on" period by the dropping of relay NC and the consequent opening of its front contact 20.

The third code digit to be received in the control office is + (pulse) in the primary indication line circuit. This is because when relay 2FP 5 drops during the second "off" period to close its back contact 92, a circuit is closed for energizing the primary indication line circuit which may be traced from the (+) terminal of battery IB, lower winding of relay MB, back contacts 23 and 21 of 10 relays PC and NC respectively, back contacts 94 and 92 of relays FP and 2FP respectively, front contacts 99 and 91 of relays FC and 2SA respectively, primary indication line conductor IL, back contact 256 of relay LO², indication line conductor IL, front contact 356 of relay LO³, front contact 372 of relay SB³, back contact 373 of relay 1F³, front contact 301 of relay MF³, resistance units 1R³ and 2R³ in series and primary indication return conductor IR to the (—) terminal of 15 20 battery IB. The primary indication line circuit is de-energized when relay NC picks up and opens the above described circuit at its back contact 21.

When the primary indication line circuit is energized during the second "off" period, relay 25 MB is picked up and maintained energized by way of its lower winding until its stick circuit is closed by the closure of back contact 65 when relay E drops to mark the end of the second "off" period. The picking up of relay 2FP closes 30 a substitute stick circuit for relay MB at its front contact 60 which is maintained after the picking up of relay E and until relay 2FP is dropped during the third "off" period.

This indication which was received on relay 35 MB in the second "off" period is executed during the second "on" period by means of a circuit extending from (B+), front contact 97 of relay MB, front contact 81 of relay FP, conductor 40 48 55 of relay 2V, conductor 30 and upper winding of relay 2PB to (B—). Relay 2PB is picked up and closes an obvious stick circuit for itself by way of its lower winding to (+) on conductor 42.

Since the three code digits above described 45 comprise the station registration code, station relay 5ST (which corresponds to station No. 5) is picked up when relay LV is picked up during the third "off" period over a circuit extending from (+), front contact 36 of relay LV, conductor 26, back contact 24 of relay 1PB, front contact 25 of relay 1PF, front contact 28 of relay 2PB and winding of relay 5ST to (—).

The transmission of the fourth code digit does not pulse the primary indication line circuit, 55 since it was assumed that contact 492 of relay T⁴ of Fig. 4 is open. It will be recalled that this fourth code digit was transmitted from the secondary field station as a — (non-pulse) because relay PB⁴ was not up during the first "on" 60 period, which resulted in relay MB³ not being picked up during the second "off" period. Since this fourth code digit is retransmitted to the control office during the second "on" period and since relay MB³ is not picked up during this 65 period, it will be obvious that the primary indication line circuit cannot be energized when the control office connects relay MF and battery IB in the primary indication line circuit during the second "on" period.

70 Therefore relay MF will remain down in response to this — fourth code digit and when this code digit is executed it effects the positioning of relay 1RF to the right by means of a circuit extending from (B—), back contact 96 of relay 75

MF, back contact 86 of relay FP, conductor 9, front contact 87 of relay FC, front contact 88 of relay VP, front contact 98 of relay 2V, conductor 39, front contact 19 of relay 5ST and winding 5 of relay 1RF to (CN). Current flow in this circuit positions the polar contact of relay 1RF to the right for displaying the proper indication that track relay T⁴ is picked up. It will be obvious that the alternate fourth code digit is transmitted when track relay T⁴ is down, which finally results in the picking up of relay MF during the second "on" period so that it is up during the third "off" period to apply (B+) over the above described circuit by way of its front contact 96 for positioning the polar contact of relay 1RF to the left.

The above illustrates how the "off" indications (choice of two) which start from a field station in the secondary section during one "off" period are received in the control office during the succeeding "on" period and executed during the succeeding "off" period. Likewise, examples are given of the manner in which "on" indications (choice of two) which leave a field station in the secondary section during an "on" period are received in the control office during the succeeding "off" period and executed during the next succeeding "on" period.

It is believed that the above examples are sufficient to indicate how these code digits are transmitted, stored, retransmitted and executed for additional steps of a cycle and it will be understood that as many such code digits may be provided as desired by increasing the number of steps taken by the stepping relay banks.

At the end of the indication cycle the last "off" period is effective to de-energize the SA and the 2SA relays as well as the VP, the E, stepping relays and the CD and C relays in the same manner previously described in connection with a control cycle. Relay FC in the control office, which is maintained picked up during an indication cycle, is likewise de-energized at the end of the cycle by the dropping of relay SA.

Lock-out.—Assuming that a field station in the secondary section has new indications to transmit to the control office when the system is in its condition of rest, the field station thus involved closes the secondary indication line circuit and this results in the picking up of relay MF³, followed by the picking up of relay LO³ at the repeater station. The picking up of relay LO³ at the repeater station closes the primary indication line circuit which picks up relay MB in the control office to initiate the operation of the system.

As a result of this field start the control office applies a conditioning (—) impulse to the primary control line circuit, which (—) impulse is repeated into the secondary control line circuit. The picking up of relay 1F³ in the primary control line circuit opens the pick-up circuit of relay LO³ at back contact 388 and leaves relay LO³ stuck up by line energy from the control office over the primary indication line circuit.

In this condition relay LO³ at the repeater station is subject to being locked out or overruled by any field station in the primary section in exactly the same manner as the lock-out between individual field stations of the primary section. In the event that relay LO³ of the repeater station is locked out by a superior field station (one nearer the control office) its release (since relay 1F³ is now picked up during the 75 conditioning period) will immediately remove

energy from the secondary indication line circuit and thus release any lock-out relay in the secondary section that happens to be picked up.

However if relay LO³ at the repeater station is not overruled by a superior station it will remain stuck up during the lock-out period by line energy from the control office until its local stick circuit is established by relay SA³ closing its front contact 358. In case relay LO³ of the repeater station is not overruled by a superior station in the primary section it will maintain energy to the secondary indication line circuit until after the lock-out has been effected between the individual stations of the secondary section. Thereafter energy to the secondary indication line circuit is applied through the pick-up coils of the MB³ and MF³ relays and through the pulsing contacts of the FN³, FP³ and 2FP³ relays, through front contact 390 of relay LO³ and front contact 396 of relay SB³.

Indication line circuit precharging.—From the foregoing description it will be observed that the indication receiving relays MF³ and MB³ at the repeater station and the indication receiving relays MF and MB in the control office are connected in the secondary indication line circuit and the primary indication line circuit respectively in such a manner that they are controlled in accordance with the open or closed condition of transmitting contacts at the secondary transmitting station and at the repeater station respectively. With such an arrangement it happens that the sequence of events is such that the distributed capacity of the indication line circuits becomes discharged so that the application of energy to these circuits may result in a temporary surge of current which is conveniently termed the charging current. This charging current flows irrespective of whether the line circuit is open or closed at the location from which an indication is to be received.

It has been found in some instances that the charging current that flows into an open circuited indication line reaches a peak value which is considerably greater than the current that normally flows under the stable conductive condition of the line circuit and that this charging current surge lasts for an appreciable length of time. Under these conditions the message receiving relay in the indication line circuit, for the purpose of detecting the conductive condition of the line, may be undesirably picked up by the charging current when such relay was supposed to remain down in accordance with the open circuit condition of the line.

During an indication cycle the secondary indication line circuit is impulsed and, in accordance with the contact arrangement comprising contacts 392, 393 and 394 of relays 2FP³ and FP³ of Fig. 3, a precharge is applied to the secondary indication line circuit.

During the transfer from one period to another, that is from an "on" period to an "off" period or vice versa, there is an interval of time during which the secondary indication line circuit is not energized from battery IB¹ and during which time the distributed capacity of the secondary indication line circuit may become discharged by reason of the closed condition of one of its controlling contacts at the field station. This is because the field station apparatus is not permitted to change the condition of the secondary indication line circuit until after this line circuit is opened at the repeater station, which is necessary to provide that the message receiving 75

relays MF³ and MB³ will be properly controlled. Thereafter the transfer at the field station occurs so that upon the closure of the secondary indication line circuit at the repeater station the conductive circuit then established is dependent upon the governing contact at the field station. Thus it is obvious that a charging current will flow at the beginning of each period which follows a period during which the secondary indication line circuit has been conductively closed at the field station, or at the beginning of a period following an interval during which the line may have been discharged for any other reason. The same discussion applies to the operation of relays MF and MB in the office with energy applied to the primary indication line circuit from battery IB.

During an "on" period, for example, relays FP³ and 2FP³ at the repeater station are picked up. Relay MF³ is energized or not depending upon the closed or open condition of contact 499 of relay PF⁴ at the transmitting station. It will be assumed that contact 499 of relay PF⁴ is closed during the first "on" period. Therefore relay MF³ will be picked up but just before it is connected into the secondary indication line circuit this line circuit is precharged.

When relay FN³ picks up at the beginning of the first "on" period in the secondary control line circuit, the indication battery IB¹ is disconnected from the secondary indication line circuit at the same instant by the opening of back contact 397. During the interval between the picking up of relay FP³ and the picking up of relay 2FP³ the indication battery is connected to the secondary indication line circuit through charging resistor CRS³ over a circuit extending from the (+) terminal of battery IB¹, resistor CRS³, front contact 394 of relay FP³, back contact 392 of relay 2FP³, front contact 390 of relay LO³ and front contact 396 of relay SB³ to the secondary indication line conductor IL¹. This connection of battery IB¹ to the secondary indication line circuit through resistance CRS³ is effective to apply a charging current to this line circuit before the winding of relay MF³ is inserted in this line circuit to detect its closed or open condition at the transmitting field station.

The first "on" code digit in the secondary indication line circuit in the above description was one during which the secondary indication line circuit was closed because relay PF⁴ was picked up during the first "off" period and maintained picked up throughout the first "on" period. Therefore since the transmission of the first "on" indication is one which requires the closed condition of the secondary line circuit it will be obvious that it was not necessary to precharge the secondary indication line circuit because the message relay MF³ was supposed to pick up during this "on" period. However, in the event that an "on" indication is transmitted which requires that this line circuit be open at the transmitting field station, the application of the charging current to the line circuit just before the message receiving relay is inserted into this line circuit charges the secondary indication line circuit to eliminate any flow of current which might be effective to falsely operate the message receiving relay when it is inserted into the circuit and supposed to remain down because of the open condition of the indication circuit.

A similar condition exists during the transmission of "off" indications, for example the secondary indication line circuit is precharged when relay FP³ is dropped and before relay 2FP³ is

dropped, over a circuit extending from the (+) terminal of battery IB¹, charging resistance CRS³, back contact 393 of relay FP³, front contact 392 of relay 2FP³, front contact 390 of relay LO³ and front contact 396 of relay SB³ to indication line conductor IL¹. The dropping of relay 2FP³ opens the above described circuit and inserts relay MB³ in the secondary indication line circuit, but before this relay is included in this circuit the circuit is precharged for the same purpose previously discussed in connection with the "on" indication condition.

A similar arrangement is provided by contacts 92, 93 and 94 of relays 2FP and FP in the control office for precharging the primary indication line circuit by way of charging resistor CRS before message receiving relays MB and MF are included in this line circuit. Since this arrangement is similar to the arrangement of the contacts of relays FP³ and 2FP³ already described, it is believed unnecessary to point out in detail how this feature operates in connection with the primary indication line circuit. It will be understood that the primary indication line circuit is dependent for its open and closed condition on contacts 391 and 399 of relays MF³ and MB³ respectively at the repeater station as selected by contact 373 of relay IF³, and in the event that the particular one of these contacts involved is open at the time the indication is to be transmitted, then the charging current applied to the primary indication line circuit in the control office is effective to prevent the false picking up of the indication receiving relay when such relay is not to be picked up.

Duplex.—The present invention is applied to a duplex type centralized traffic controlling system such as disclosed in the above mentioned prior application 640,062. The operations for separate control and indication cycles have been described and it will now be briefly pointed out how the system operates when controls and indications are transmitted on the same cycle.

The actuation of a starting button in the control office results in the picking up of the associated CD relay during the time that the system is at rest and any time up to the end of the period marked off by the picking up of relay 2SA in the control office. When a field station initiates the system the relays are conditioned during the conditioning period as described in connection with an indication cycle.

After the 2SA relay in the control office is picked up due to a field station initiating the cycle, then the office must wait until the next condition of rest of the system before it can pick up a CD relay for the transmission of controls. This means that a cycle initiated by the picking up of a CD relay may be converted into a duplex cycle by a field station any time up to the picking up of relay 2SA. In this connection however it will be noted that relay C in the control office is picked up by the operation of the starting button so that the picking up of relay FC is ineffective to directly control relay NC because of open back contact 41 of relay C.

Since a field station can energize its lock-out relay any time up to the picking up of its associated FP relay, it will be seen that a field station may be in condition to transmit its indications during the same cycle that the control office transmits controls because relay CD can be picked up during the initiating period of a cycle initiated from a field station. Similarly the control office can pick up its CD relay for trans-

mitting controls in the conditioning period of a cycle initiated by a field station. Furthermore, both an office start and a field start condition may be waiting when the system goes into its 5 normal condition following an operating cycle.

With relay CD picked up and a field station having its lock-out relay picked up at the start of a particular cycle, the first impulse in the control lines is (+) or (-) as determined and 10 described in Ser. No. 640,062 in connection with a control cycle. This first impulse picks up the SO relays at the proper stations and determines that stepping at these stations will be started. The character of the impulses applied to the 15 control line circuits as determined by the particular CD relay which is picked up selects the required station by dropping out the SO relays at the stations not to be selected in the manner described in Ser. No. 640,062. Since a lock-out 20 relay such as relay LO⁴ of Fig. 4 is assumed picked up, stepping will continue at the associated station in the event that it is not the selected station for controls because of the closure of a front contact of relay LO⁴ not shown 25 in the present disclosure but which is illustrated in Ser. No. 640,062.

The resulting cycle of operations is thus the same in-so-far as the transmission of impulses over the control line circuits for the selection of a 30 station is concerned as was previously described in connection with a control cycle alone. Similarly the resulting operations of the cycle in-so-far as the conditioning of the indication line circuits is concerned is the same as described for 35 a cycle during which indications alone were transmitted. Since transmission over the control and indication line circuits is effected during duplex cycle by separate and distinct circuit instrumentalities it is obvious that these transmissions 40 may be combined and brought about during a single cycle of operations, conveniently referred to as a duplex cycle.

Secondary control line continuity test.—The 45 circuits at the repeater (Fig. 3) are so arranged that the secondary control line circuit is tested for continuity at the beginning of each cycle. In the event that the secondary control line circuit is open the stations in the secondary section will fail to step, in which event it is desired to release 50 relay LO³ at the repeater at the earliest possible moment in order to prevent the code of a more superior station from being impressed upon the primary indication line circuit because of the continued existence of the start condition in the 55 secondary indication line circuit. It will be obvious that failure to release relay LO³ in the event of an open secondary control line circuit would effect the transmission of a code combination of all + digits (pulse) to the control office irrespective of the code combination of the secondary 60 station which may have initiated the system into operation over the indication line circuits.

When relay PC or NC picks up at the beginning 65 of the conditioning "on" period, relay S³ is picked up over an obvious circuit including front contact 366 or front contact 365. At this same instant energy is applied to the secondary control line circuit and if this line circuit is 70 closed, quick acting relay FN³ will be picked up before slow acting relay S³ so that back contact 383 will be open before the closure of front contact 386.

However, if the secondary control line circuit 75 is open, relay FN³ will fail to pick up and under

this condition a pick-up circuit for relay FP³ is closed which extends from (+), front contact 382 of relay LO³, back contact 383 of relay FN³, front contact 386 of relay S³, back contact 385 of relay SA³ and winding of relay FP³ to (-). The picking up of relay FP³ opens the line stick circuit for relay LO³ at back contact 375 which at this time includes the primary indication line circuit. At this time the pick-up circuit of relay LO³ is open at back contact 388 of relay IF³ and consequently relay LO³ is released, after which relay FP³ is released because of open front contact 382 of relay LO³. This sequence of events prevents the coding of the primary indication line circuit in the event that the secondary control line circuit is 15 open at the beginning of a cycle during which indications are to be transmitted. This may be readily seen by referring to Fig. 4 in which the lockout relay LO⁴ may be picked up by the change relay CH⁴ and is maintained picked up by such 20 change relay continuously if that station does not receive impulses over the control line to operate the relay F⁴ and cause the various sequences in the lockout period to occur. So long as the lockout relay LO⁴ is picked up and the relay SB⁴ is dropped 25 away, as it would be in the event that the line relay F⁴ does not receive control impulses, then a circuit is closed between the line wire IR¹ and IL¹ through front contact 456 of relay LO⁴, back contact 472 of relay SB⁴, and lower winding of relay 30 LO⁴. This closed circuit condition across the line wires will be repeated into the repeater station of Fig. 3 and cause the relays MF³ and MB³ to be controlled in such a manner as to impress 35 the code of the most superior station in the system, namely, the code for the station No. 1 as can be seen in Fig. 1. It is believed unnecessary to point out this sequence of events in the repeater station in Fig. 3 under such circumstances as such events appear only in the case of failure and the 40 contemplated operation has been pointed out in detail above. It is believed to be sufficient to say that this check on the continuity of the secondary control line circuit insures that an erroneous 45 code is not transmitted through the repeater station in the event of the open condition of the secondary control line circuit because of the failure of a start condition to be properly handled during the lockout period.

Having thus described one specific embodiment of a centralized traffic controlling system it is desired to be understood that the particular arrangement illustrated is merely typical of applicant's invention and is not intended to follow the exact circuit design necessary to carry 55 out the features of the invention, but has been selected to facilitate in the disclosure rather than to limit the scope of the invention and it is further to be understood that various modifications may be made and various adaptations and 60 alterations may be applied to the specific form disclosed in order to meet the various problems encountered in practice and that the system may be varied in the number of repeater and field stations, the amount of apparatus installed at the 65 particular repeater and field stations and the number of steps provided for station selection, station registration, control and indication codes transmitted, all without in any manner departing from the spirit or scope of the invention except as limited by the appended claims.

What I claim is:

1. In a remote control system, a control office, a plurality of stations, a first control line circuit and a first indication line circuit connecting said 75

- office with a first one of said stations, a second control line circuit and a second indication line circuit connecting said first station with a second one of said stations, means in said office for applying a first series of time spaced impulses to said first control line circuit, means at said first station for applying a facsimile of each of said impulses and time spaces to said second control line circuit, means at said second station for opening or closing said second indication line circuit during each impulse period and each time space period in accordance with indications to be transmitted, means at said first station for receiving the open or closed conditions of said second indication line circuit, means at said first station for storing the received conditions of said second indication line circuit, and means for transmitting each condition stored during an impulse period and a time space period to said office during a succeeding time space period and succeeding impulse period respectively by correspondingly opening or closing said first indication line circuit.
2. In a remote control system, a plurality of locations including a control office and a plurality of field stations, a primary control line circuit and a primary indication line circuit connecting said office with a first one of said stations, a secondary control line circuit and a secondary indication line circuit connecting said first station with a second one of said stations, means in said control office for controlling the application of a series of time spaced control impulses to said control line circuits, means at said field stations responsive to said control impulses, whereby control messages are transmitted between said locations, two code transmitting means at each of said stations for transmitting messages over said indication line circuits, means rendering one of said code transmitting means at a first one of said stations effective during each impulse of a first series on said secondary control line circuit, means rendering the other of said code transmitting means at said first station effective during each time space of said first series, means for receiving and storing at a second one of said stations messages transmitted by said one code transmitting means, and means controlled by the stored message and including the code transmitting means at said second station for transmitting the stored message over said primary indication line circuit to said office during time space and impulse periods immediately succeeding the impulse and time space periods respectively in which said message was stored.
3. In a repeater system, a first control line circuit and a second control line circuit, an indication line circuit, means for applying a series of primary impulses to said first control line circuit, means responsive to said primary impulses for applying a series of secondary impulses to said second control line circuit, testing means controlled jointly by said first and second control line circuits for testing the continuity of said second control line circuit, and means responsive to the open or closed condition of said second control line circuit as determined by said testing means for distinctively controlling said indication line circuit.
4. In a remote control system; a control office; a first plurality of field stations; a second plurality of field stations; a repeater station; a first control line circuit connecting said control office, said first plurality of field stations and said repeater station; a second control line circuit connecting said repeater station and said second plurality of field stations; a first indication line circuit connecting said control office, said first plurality of field stations and said repeater station; a second indication line circuit connecting said repeater station and said second plurality of field stations; means in the control office for applying different series of control impulses to said first control line circuit; means at the repeater station responsive to each said series of impulses on said first control line circuit for applying a similar series of impulses on said second control line circuit; code transmitting means at each of said field stations for transmitting codes over its respective indication line circuit when rendered effective by a series of impulses on its respective control line circuit; means at said repeater station for repeating each code on said second indication line circuit into said first indication line circuit; testing means at said repeater station controlled jointly by said first and second control line circuits during the first impulse of each series of impulses for testing the continuity of said second control line circuit; and means controlled by said testing means, if said second control line circuit is found open, to prevent said code transmitting at each of said field stations in said second plurality from being rendered effective to transmit on the remaining impulses of such series.
5. In a remote control system; a control office; a first plurality of field stations; a second plurality of field stations; a repeater station; control line circuit means connecting said control office, said first plurality of field stations, said repeater station, and said second plurality of field stations, and having a series of time spaced impulses impressed thereon; a first indication line circuit connecting said control office, said first plurality of field stations and said repeater station; a second indication line circuit connecting said repeater station and said second plurality of field stations; step-by-step means at said control office and at each of said field stations, all operated in synchronism step-by-step in response to said series of impulses on said control line circuit means; code transmitting means at each of said field stations for transmitting a code element over its respective indication line circuit on each impulse period and each time space period marked off by said impulses on said control line circuit means; storing means at said repeater station for storing each code element transmitted over said second indication line circuit; and means at said repeater station for impressing a code element on said first indication line circuit for each time space and each impulse period marked off on said control line circuit means, said code element being identical to the code element received on the preceding impulse and time space periods respectively.
6. In a remote control system; a plurality of locations including a control office, a primary station and a secondary station; separate line circuits interconnecting said locations including a primary line circuit connecting said control office and said primary station, and a secondary line circuit connecting said primary station and said secondary station; stepping mechanisms at said control office and at said stations; means for operating said mechanisms through a plurality of cycles of operation in synchronism; means at said primary station effective for a predetermined number of steps of a particular one of said cycles of operation for distinctively conditioning said

primary line circuit to form a primary code; means at said secondary station effective for said predetermined number of steps, except the last, of another of said cycles of operation for distinctively conditioning the secondary line circuit to form a secondary code; storage means for storing the condition of said secondary code on said secondary line circuit for each step into said primary line circuit during the next succeeding step of said other cycle of operation and in so doing to add a code element to said secondary code for said first step; and means in said control office controlled by said primary and secondary codes for identifying said primary and said secondary stations respectively.

7. In a remote control system, step-by-step mechanisms located at a control office and each of a plurality of stations, means for operating all of said mechanisms through cycles of operation in synchronism, a first line circuit connecting said control office and a first of said stations, a second line circuit connecting the first station with a second station, a third line circuit connecting the second station with a third station, code transmitting means at said third station capable of transmitting code impulses over said third line circuit on certain steps of said mechanism at that station, storage means at said second station controlled by the code impulses on said third line circuit on each step of said mechanism at that station and capable of repeating said code impulse into said second line circuit on the next succeeding step, storage means at said first station controlled by the code impulse on said second line circuit on each step of said mechanism at that station and capable of repeating said code impulse to said first line circuit on the next succeeding step, and means at said control office controlled by said impulse on said first line circuit on each step of said mechanism.

8. In a remote control system; a control office; a first plurality of field stations; a second plurality of field stations; a repeater station; control line circuit means connecting said control office, said first plurality of field stations, said repeater station, and said second plurality of field stations, said line circuit means having a plurality of series of impulses impressed thereon; a first indication line circuit connecting said control office, said first plurality of field stations and said repeater station; a second indication line circuit connecting said repeater station and said second plurality of field stations; a normally at rest step-by-step mechanism at said control office and each of said field stations; means whereby said step-by-step mechanisms are operated in synchronism through a cycle of operation by a series of impulses on said control line circuit means; code transmitting means at each of said first plurality of field stations for impressing a code element on its respective indication line circuit for each step of its said step-by-step mechanism; code transmitting means at each of said second plurality of field stations for impressing a code element on its respective indication line circuit for

each step of its said step-by-step mechanism except the last; storing means at said repeater station for storing on each step of a cycle of operation the code element impressed on said second indication line circuit for that step, said storing means being capable of storing either of two different code elements and normally assuming while the system is at rest a condition as if one of said two different elements were stored in it; means at said repeater station for impressing a code element on said first indication line circuit during each step of a cycle of operation, the code element for the first step corresponding to the normal condition of said storing means and the code elements for each remaining step being the same as the code element stored in said storing means for the preceding step, whereby there is the same number of code elements for a cycle of operation, when one of said field stations from said second plurality of field stations is transmitting, as there is when one of said field stations from said first plurality is transmitting; and means allowing the operation of the transmitting means at only one of said field stations of both pluralities to transmit for any given cycle of operation.

9. In a remote control system; a control office; a repeater station; a plurality of field stations; control line circuit means connecting said control office, said repeater station, and said plurality of field stations and having a plurality of series of time spaced impulses impressed thereon; a first indication line circuit connecting said control office and said repeater station; a second indication line circuit connecting said repeater station and said plurality of field stations; step-by-step means at said control office and at each of said field stations, all operated in synchronism step-by-step in response to a series of impulses on said control line circuit means; code transmitting means at each of said field stations for opening or closing said second indication line circuit during each impulse period and each time space period in accordance with indication conditions to be transmitted from that station, said code transmitting means including said step-by-step means at such station; one storage relay at said repeater station controlled in accordance with the open or closed condition of said second indication line circuit during each time space period and maintained in such condition during the following impulse period; another storage relay at said repeater station conditioned in accordance with the opened or closed condition of said second indication line circuit during each impulse period and maintained in such condition during the following time space period; and means at said repeater station for opening or closing said first indication line circuit for each impulse space period in accordance with the condition stored in said one storage relay and for opening or closing said first indication line circuit for each time space period in accordance with the condition stored in said another storage relay.

DARROL F. DE LONG.
